(57) CLAIM

The ornamental design for a display screen with graphical user interface, as shown and described.

DESCRIPTION

FIG. 1 is a front view of a display screen with graphical user interface showing my new design; and,

FIG. 2 is an enlarged view of the region surrounded by an uneven-length broken line in FIG. 1.

The broken line showing of the text, the various icons, the remainder of the user interface and the remainder of the display screen is for environmental purposes only and forms no part of the claimed design. The dot-dash line defines the bounds of the claimed design and forms no part thereof.
